UNITED STATES PATENT OFFICE

ALBERT J. PAYNTER, OF ALTON, KANSAS.

SAFETY DEVICE FOR RAILROAD-CROSSINGS.

1,280,532.

Specification of Letters Patent.

Patented Oct. 1, 1918.

Application filed December 7, 1917. Serial No. 206,054.

To all whom it may concern:

Be it known that I, ALBERT J. PAYNTER, a citizen of the United States, residing at Alton, in the county of Osborne and State 5 of Kansas, have invented new and useful Improvements in Safety Devices for Railroad-Crossings, of which the following is a specification.

This invention relates to improvements in 10 safety devices for railroad crossings, and contemplates the provision of a simple, reliable, and effective crossing barrier and signal which will be automatically operated by the passage of trains. It is further proposed to improve the operating mechanism by eliminating the use of electricity, and to 15 incorporate therein a simple and effective device whereby the signal-setting device will only be operated by a car passing in one 20 direction.

One embodiment of the invention whereby the above enumerated ends are effected is described in the specification below and 25 illustrated in the drawings, the original features being pointed out in the claims.

In the drawings—

Figure 1 shows a railroad crossing provided with the barrier and signal comprised in the present invention. 30 Fig. 2 is a fragmentary side elevation of the signal arm and supporting structure, showing parts of the mechanism for moving the arm to the safety position, and the retaining device for the arm.

Fig. 3 is an end view of the arm and supporting structure.

Fig. 4 is a fragmentary view illustrating the portions of the setting device associated with the track rail, and

Fig. 5 shows the tripping device and loose coupling in detail.

Referring to the drawings more specifically, the signal has a supporting structure shown in the drawings as a post or standard 45 1 bifurcated toward the upper extremity for receiving the barrier and signal arm 2 pivotally mounted toward one end for movement in a vertical plane by means shown as a bolt 3 passing through the arm and stand- 50 ard.

To normally retain the arm 2 in an upward position indicative of safety, a catch 4 is pivotally attached to the face of the standard 1 and provided with a spring 5 55 whereby it is maintained in the path of the long end of the arm 2. The catch 4 is con-

nected by a link 6 to a bell-lever 7 pivotally mounted in the present instance on the side of the standard toward the base. From the other arm of the bell-lever 7 suitable connecting means shown as a wire 8 extends toward a contact element illustrated as a trip lever 9 pivotally attached to a track-rail 10 at a suitable distance, with the upper end in position to be struck by the wheels of a train. 60 Attached to the lower extremity of the trip lever 9 and the end of the wire 8 is a loose coupling 11 preferably including a spiral spring 12 of suitable strength to maintain the wire 8 tightly stretched and a second 70 spring 13 is provided, tending in the opposite direction to maintain the trip-lever 9 in the path of the wheels of a car.

It will be seen that in the passage of a car in one direction, the catch 4 will be released 75 to permit the long end of the arm to move downward to a position indicative of danger, while in the passage of a car in the other direction no result will follow.

To restore the arm 2 to the upward position a lever 14 has one end pivotally mounted in proximity to the track and the other end extended toward the standard 1 and provided with an upwardly disposed arm 15 terminally connected by a link 16 to the 80 short end of the semaphore arm 2.

Overlying the lever 14 toward the pivoted end is a bar 17 mounted at one end for vertical swinging movement and having the other end disposed adjacent a rail in a position to be depressed by the wheels of a train to force the lever 14 downwardly against a spring 18 and elevate the arm 2. The lever 14, arm 15 and link 16 are of suitable length, and the link 16 attached to the arm 2 at such 85 a point that when the arm 2 is maintained in the elevated position by the catch 4 the lever is permitted free upward movement, while in the lowermost position of the arm the weight of the arm is sustained by the link 100 and lever to maintain it in horizontal position.

It will be obvious that by providing a second trip-lever disposed on the other side of the crossing and similarly connected to the catch, the device may be utilized for trains in either direction.

The herein-described embodiment of the invention is intended merely for purposes of illustration, and is not to be interpreted as in any way limiting the spirit or scope of the invention, such limitation being confined

to that indicated by the latitude of the claims.

Manifestly the arm 2 is adapted to serve the two-fold purpose of signal arm and barrier, Fig. 1, though I do not limit myself to the employment of an arm sufficiently long to serve as a barrier.

What I claim is—

1. The combination with a railroad crossing arm, of a lever disposed parallel to a track rail and having linked connection at one end to the arm, a pivotally mounted trip-bar overlying the lever with one end in juxtaposition to the track rail, whereby in 10 the passage of a car the lever will be actuated to operate the arm to safety position, means for retaining the arm in the safety position, and car-operated means for releasing the last-mentioned means to allow the 15 arm to move to danger position.

Copies of this patent may be obtained for five cents each, by addressing the "Commissioner of Patents, Washington, D. C."

2. The combination with a railroad crossing arm, of a lever disposed parallel to a track rail and having linked connection to the arm, a pivotally mounted trip bar overlying the lever with one end in proximity 25 to the rail, a spring pressed catch on the arm support normally disposed in the path of the arm to retain the arm in the safety position, a contact element pivoted in proximity to the track rail, connecting means between 30 said element and said catch whereby in the actuation of said element by a car moving in one direction the catch will be displaced from the path of the arm, and a loose coupling in said connecting means whereby said 35 contact element will not be affected by the actuation of said element by a car moving in the other direction.

In testimony whereof I affix my signature.

ALBERT J. PAYNTER.
